ABSTRACT: In apparatus to write a code signal generated by code signal-generating means such as a switch located at a measuring point into a computer, an insulation transformer is connected between the code signal-generating means and an output circuit. A series diode and a parallel capacitor are connected to a circuit interconnecting the primary winding of the insulation transformer and the code signal-generating means. A pulse is normally applied to the secondary winding of the insulation transformer to charge the capacitor through the diode. The capacitor is discharged when the switch is closed to decrease the secondary impedance of the transformer to produce an output signal corresponding to the code signal.

CODE SIGNAL INPUT APPARATUS

BACKGROUND OF THE INVENTION

This invention relates to a code signal input apparatus to write code signals generated by the opening and closing operation of a contact into a data processing apparatus such as an electronic computer.

In the electronic computer control system, in order to write code signals generated by the operation of a contact installed at a measuring point into the computer it is necessary to provide DC insulation between the computer and the contact at the measuring point. For this purpose, it has been the practice to write code signals into the computer through a transistor switch which is controlled to become ON and OFF by DC voltages corresponding to the code signals generated by the apparatus installed at the measuring point. However, this circuit arrangement is complicated and its reliability is low.

SUMMARY OF THE INVENTION

It is an object of this invention to provide a novel code signal input apparatus for a computer which is simple in construction, can be manufactured at low cost and has improved reliability.

According to this invention there is provided a code signal input apparatus comprising code signal-generating means such as an electric switch associated with apparatus at remote measuring point, an insulation transformer connected between the code signal-generating means and a computer, a diode connected in the circuit interconnecting the primary winding of the insulation transformer and the signal-generating means, and a capacitor connected across the primary winding to store the condition of the code signal, the polarity of the diode being selected such that the diode responds to the voltage across the capacitor to write the code signal into the computer. An impulse is normally applied to the secondary winding of the insulation transformer to charge the capacitor to a predetermined value. When the switch or code signal-generating means located at a measuring point is closed the capacitor is shorted by the switch to decrease the secondary impedance of the insulation transformer, thus generating a signal corresponding to the code signal generated by the switch.

BRIEF DESCRIPTION OF THE DRAWINGS

In the accompanying drawings:

FIG. 1 is a connection diagram of one embodiment of the code signal input apparatus embodying this invention;

FIG. 2 is a connection diagram of a modified embodiment of this invention;

FIG. 3 shows a set of waveforms to explain the operation of the apparatus shown in FIG. 1 and

FIG. 4 shows a set of waveforms to explain the operation of the apparatus shown in FIG. 2.

DESCRIPTION OF THE PREFERRED EMBODIMENTS

A preferred embodiment of this invention illustrated in FIG. 1 comprises a plurality of switches S_1 , S_2 and S_n installed at measuring points for generating code signals. Across signal lines controlled by switches S_1 , S_2 , S_n are connected capacitors C_1 , C_2 , C_n and the signal lines are connected to the primary windings of insulation transformers T_1 , T_2 , T_n , respectively, through diodes D_1 , D_2 , D_n . One terminal of the secondary windings of insulation transformers T_1 , T_2 , T_n is connected to one input terminals of AND-gate circuits G_1 , G_2 , G_n and also to the common output terminal of an inverter IV. The other terminal of the secondary windings of the insulation transformers are connected to one pole of a DC source having the other terminal grounded. An input terminal of readout signals INR is connected to the other input terminals of the AND-gate circuits G_1 , G_2 , G_n and to one input terminal of an OR-gate circuit G_0 . The output of an oscillator OS is connected to the

other input terminal of the OR-gate circuit G_0 and the output thereof is supplied to the input terminal of the inverter circuit IV. The output terminals of the AND-gate circuits are connected to output terminals O_1 , O_2 , O_n of the code signals.

5 The operation of the code signal input apparatus shown in FIG. 1 is as follows:

The contacts of the code signal-generating switches S_1 , S_2 , S_n installed at the measuring points are controlled corresponding to the code signals to be sent to the computer. The pulse oscillator OS generates a pulse signal of a given frequency as shown in FIG. 3b, to apply the pulse signal to the input terminal of inverter circuit IV, through OR-gate circuit G_0 . To read out the conditions of contacts of switches S_1 , S_2 , S_n at the measuring points and write them into the computer, a readout signal as shown in FIG. 3c is applied to the readout signal input terminal INR and this signal is impressed upon the input terminal of the inverter circuit IV which functions to invert the output signal from the oscillator OS as shown in FIG. 3b, and the signal applied to the readout signal input terminal INR as shown in FIG. 3c to produce a signal of the waveform as shown in FIG. 3d. This signal is applied to one terminal of the secondary windings of insulation transformers T_1 , T_2 , T_n respectively through resistors R_1 , R_2 , R_n . As a consequence, 10 15 20 25 30 35 40 45 50 55 60 65 70 75 AC signals corresponding to the output signal of the inverter circuit IV are induced in the primary windings of respective insulation transformers and these AC signals are rectified by diodes D_1 , D_2 , D_n to charge capacitors C_1 , C_2 , C_n respectively.

Where switches S_1 , S_2 , S_n are opened, capacitors C_1 , C_2 , C_n

will be charged by a definite voltage V_c corresponding to the crest value of the output signal from the inverter circuit IV as shown in FIG. 3a, whereas when the switches are in their closed state, the condensers are shorted by the switches so that they will not be charged. In this manner, when the

switches are opened, diodes D_1 , D_2 , D_n are reversely biased by the voltage V_c of capacitors C_1 , C_2 , C_n and hence are maintained OFF to open the circuits through the primary windings of insulation transformers T_1 , T_2 , T_n . This reflects in the increase in the secondary impedance of the insulation transformers.

40 Since no current flows through the primary winding no voltage drop appears across resistors R_1 , R_2 , R_n that no output signal appears at output terminals O_1 , O_2 , O_n as shown on the left-hand half of FIG. 3e even when a signal shown in FIG. 3c is impressed upon readout signal input terminal INR. On the other hand, when switches S_1 , S_2 , S_n are closed capacitors C_1 , C_2 , C_n are short circuited and their terminal voltage is zero so that diodes D_1 , D_2 , D_n are in their conductive state to short circuit the primary windings of the insulation transformers. For this reason, the secondary windings are maintained at low impedance condition so that the junctures between the secondary windings and respective resistors R_1 , R_2 , R_n are at the voltage V of the DC source E. Under these conditions upon application of a signal shown in FIG. 3c on the signal readout terminal INR, gate circuits G_1 , G_2 , G_n are opened or enabled to read out the voltage V at the junctures onto output terminals O_1 , O_2 , O_n through gate circuits G_1 , G_2 , G_n as shown on the right-hand portion of FIG. 3e. In this manner, code signals represented by the ON, OFF conditions of the switches S_1 , S_2 , S_n installed at the measuring points are read out on output terminals O_1 , O_2 , O_n as signals (shown in FIG. 3e) corresponding to the ON, OFF conditions of the switches by the signal readout signal (FIG. 3c) impressed upon signal readout terminal INR.

60 As can be clearly noted from the foregoing description, according to the code signal input apparatus of this invention a pulse signal is normally impressed upon the secondary winding of a transformer for providing DC insulation between a code signal-generating switch installed at a measuring point and the

70 AC component of the impulse is rectified by a diode on the primary side of the insulation transformer to charge a capacitor, which is utilized as a DC source for biasing the diode. This arrangement eliminates a DC source to be installed at the measuring point. Further where a number of code signal-generating switches are used they are completely isolated

from each other. When compared with conventional apparatus it is not only possible to greatly simplify the construction but also to reduce its manufacturing cost and to greatly improve the reliability. Thus the novel code signal input apparatus is suitable for many applications where it is required to write code signals generated in accordance with ON, OFF conditions of switches into computers.

FIG. 2 shows a modified code signal input apparatus embodying this invention. In this embodiment DC source $E_1, E_2, \dots, E_n$ are connected to input terminals of respective switches $S_1, S_2, \dots, S_n$ to constitute level signal-generating circuits which are associated with machines and apparatus installed at a remote station. In the same manner as in FIG. 1 these switches are connected to the primary windings of insulation transformers $T_1, T_2, \dots, T_n$ through diodes $D_1, D_2, \dots, D_n$ and capacitors $C_1, C_2, \dots, C_n$. One terminal of the secondary windings of insulation transformers are commonly connected to an input terminal V_c of a DC voltage while the other ends to one input terminal of AND-gate circuits $G_1, G_2, \dots, G_n$, respectively and to the output terminal of an inverter circuit IV through resistors $R_1, R_2, \dots, R_n$, respectively. A readout signal input terminal INR is connected to respective input terminals of AND-gate circuits $G_1, G_2, \dots, G_n$ and further to the input terminal of the inverter circuit IV. Output terminals of AND-gate circuits $G_1, G_2, \dots, G_n$ are connected to output terminals $O_1, O_2, \dots, O_n$, respectively.

The modified embodiment shown in FIG. 2 operates as follows:

The contacts of code signal-generating switches $S_1, S_2, \dots, S_n$ associated with remote machines and apparatus are opened or closed in accordance with code signals to be sent to the computer. When closed (ON) these switches send the voltage V of DC sources $E_1, E_2, \dots, E_n$ over associated transmission lines whereas when opened (OFF) they short circuit the transmission lines. Thus, by the ON, OFF operations of switches $S_1, S_2, \dots, S_n$ code signals as shown in FIG. 4a are sent out.

When switches $S_1, S_2, \dots, S_n$ are closed (ON) capacitors $C_1, C_2, \dots, C_n$ are charged by DC sources whereas when the switches are opened (OFF) they short circuit capacitors $C_1, C_2, \dots, C_n$ so as not to charge them. In this manner, as shown in FIG. 4b capacitors $C_1, C_2, \dots, C_n$ are charged to a voltage corresponding to code signals. To write the conditions of code signals generated in this manner into the computer, a write signal shown in FIG. 4c is applied to a write signal input terminal INR. This signal is inverted by the inverter circuit IV, and the output from the inverter circuit of a waveform as shown in FIG. 4d is supplied to one terminals of the secondary windings of insulation transformers through resistors $R_1, R_2, \dots, R_n$, respectively. This induces pulse signals in the primary windings of the insulation transformers, said pulse signals performing ON, OFF control of diodes according to the charging conditions of capacitors $C_1, C_2, \dots, C_n$.

As above described, when switches $S_1, S_2, \dots, S_n$ are maintained ON capacitors $C_1, C_2, \dots, C_n$ are charged to a constant voltage V by DC sources $E_1, E_2, \dots, E_n$ as shown in FIG. 4a whereas when switches $S_1, S_2, \dots, S_n$ are opened (OFF) capacitors $C_1, C_2, \dots, C_n$ are short circuited so that their terminal voltage are zero. As a result, so long as switches $S_1, S_2, \dots, S_n$ are in their ON state, diodes $D_1, D_2, \dots, D_n$ are reversely biased by the voltages V across capacitors so that these diodes are maintained OFF to maintain the primary windings of the insulation transformers in their opened condition. This results in a high impedance of the secondary windings of the insulation transformers and since no current flows through the primary

windings thereof high negative voltages t_1 shown in FIG. 4e will be applied across resistors $R_1, R_2, \dots, R_n$. For this reason, even when a signal shown by FIG. 4c is impressed upon the signal readout terminal INR no pulse signal will be produced at output terminals $O_1, O_2, \dots, O_n$ as shown at t_1 of FIG. 4f. Conversely, when switches $S_1, S_2, \dots, S_n$ are in their OFF condition, since capacitors $C_1, C_2, \dots, C_n$ are short circuited and their terminal voltages are zero, impression of a pulse voltage upon the secondary windings of the insulation transformers causes diodes $D_1, D_2, \dots, D_n$ to become conductive to short circuit the primary windings of insulation transformers. Thus the secondary windings of these transformers are maintained in their low impedance conditions, the junctures between the lower terminals of the secondary windings and resistors $R_1, R_2, \dots, R_n$ are maintained substantially at the voltage of the DC input terminal as shown at t_2 in FIG. 4e. Under these conditions when a signal as shown in FIG. 4c is impressed upon one input terminals of AND-gate circuits $G_1, G_2, \dots, G_n$ through readout signal input terminal INR, the voltages V_c at said junctures are read out on output terminals $O_1, O_2, \dots, O_n$ through AND-gate circuits $G_1, G_2, \dots, G_n$ as shown at t_2 of FIG. 4.

In this manner code signals generated by switches at remote measuring points are read out on to output terminals as output signals shown in FIG. 4e.

While the invention has been shown and described in terms in some preferred embodiments, it will be clear that the invention is by no means limited to these particular embodiments and that many changes and modifications will occur to one skilled in the art without departing from the true spirit and scope of the invention as defined in the appended claims.

What is claimed is :

1. Code signal input apparatus comprising code signal-generating means, an insulation transformer connected between said code signal-generating means and a computer, a diode connected in the circuit interconnecting the primary winding of said insulation transformer, and said code signal-generating means, and a capacitor connected across said primary winding to store the condition of said code signal, the polarity of said diode being selected such that said diode responds to the voltage across said capacitor to write said code signal into said computer.

2. Code signal input apparatus comprising a plurality of code signal-generating switches which generates code signals by the opened and closed conditions of their contacts, transmission lines each including a diode and a capacitor, insulation transformers respectively connecting said switches to data processing means of a computer through said transmission lines, means to normally supply a pulse signal to the secondary windings of said insulation transformers to charge said capacitors through said diodes to cause said capacitors to act as bias sources for said diodes whereby to vary the impedances of the secondary windings of said insulation transformers in response to the closed and opened conditions of said switches to read said code signals generated by the opening and closing of said switches.

3. The code signal input apparatus according to claim 2 which further comprises an inverter to invert said pulse signal so as to apply the inverted signal to one terminal of said secondary windings of said insulation transformers respectively through resistors, means to apply a DC voltage to the other terminals of said secondary windings and AND-gate circuits, one input of said AND-gate circuits being connected to said one terminal of said secondary windings and the other input of said gate circuits being connected to receive said pulse signals.
